GOVERNOR WITH SWITCH CONTROL

William J. Williams, Wilmette, Ill.

Application April 7, 1945, Serial No. 587,081

9 Claims. (Cl. 200—80)

1

This invention relates to governors with circuit controlling means adapted to open, close, or transfer circuits at predetermined speeds of rotation of an engine or other rotary element. My invention is for use in operating transmissions, clutches, valves, and the like and an object of the invention is to provide an efficient improved type of governor mechanism producing a straight line curve of movement of the control member upon increasing and decreasing speeds of rotation in combination with the operation of switch or circuit control means and the fine adjustment of the action of the entire mechanism. Moreover, my invention provides a mechanism of the type indicated in which the driving shaft thereof continues operation after certain circuits have been actuated and I have provided means to take the increased thrust developed after the operating point has been reached.

Another object of my invention is to provide an efficient governor and control mechanism for two stage operations actuating a plurality of switching means in seriatim to effect various predetermined changes in mechanism both upon an increasing and a decreasing speed of rotation of the governor shaft or other driven member.

Further objects and advantages are within the scope of this invention such as relate to the arrangement, operation, and function of the related elements of the structure, to various details of construction and to combinations of parts, elements per se, and to economies of manufacture and numerous other features as will be apparent from a consideration of the specification and drawing of a form of the invention, which may be preferred, in which:

Figure I is a vertical elevation partly in section with the parts at rest of one embodiment of my invention;

Figure II is a vertical sectional view with the parts shown in operation with the governor plunger tripping the switch;

Figure III is a similar view with the parts shown at still higher speeds of rotation;

Figure IV is a fragmentary top plan view of the governor mechanism showing means to prevent rotation of the bearing casing as seen from along the line IV—IV of Figure I;

Figure V is a sectional elevation of another embodiment of my invention with a two stage switch operating mechanism with the parts at rest;

Figure VI is an enlarged sectional view of the embodiment of Figure V with the parts in position to operate the first of the two switches;

2

Figure VII is a similar sectional view of the parts in position to operate the second switch;

Figure VIII is a similar sectional view with the parts shown in position at still higher speeds of revolution of the governor shaft; while

Figure IX is a cross sectional plan view on the line IX—IX of Figure V;

Figure X is a sectional view of a modification of the governor plunger top bearing usable with both embodiments;

Figures XI, XII, and XIII are curves showing performance due to various adjustments of both the adjusting ring and the differential in the two stage switch action;

Figure XIV illustrates a sectional view of one type of snap switch which I employ.

Referring to Figures I to IV, I have shown a governor and control mechanism housing 5 made in three parts as illustrated, having an upper

20 part which is adjustable with respect to the bottom part carrying the governor mechanism. By providing the three part housing 5, I am enabled to permit the installation of the governor and switching arrangement to be driven by an engine

25 or other source of power from which the parts are driven and the final adjustment for the action of the switching means provided herein can be made while the engine or other driving source is running. To this end, the base 6 carries the 30 knurled adjusting ring 7 which may be secured in position by the hold down clip 8. The ring 7 is screw threaded as shown to receive the threaded top cap 9 to be locked in adjusted position by the locking screws 10 as shown.

35 For example, in installation the top part of the housing being connected with circuit control means has wiring connected thereto so that it is undesirable to adjust the top part of the housing 5 while the engine is running. However, by

40 unloosing the clips 8, the knurled ring 7 may be turned after the set screws 10 have been unloosed and a satisfactory adjustment made as this will move the upper part of the housing away from the ring and hence, away from the governor plunger so that the operation of the switches will occur at different times according to the adjustment. After the adjustment is made, the set screws 10 are located and the hold down clips are fixed in position so that the mechanism will not thereafter get out of adjustment.

45 Within this housing 5 mounted in a suitable bearing 12 is the governor shaft 12, the revolutions of which may vary by being connected with some mechanism whose speed varies. The shaft 12 carries within the housing, the rotatable sup-

port 14 for the governor weights 15, the support 14 being pinned to the shaft 12 in the illustration. These governor weights 15 are pivoted as at point P to the support 14 so that under the centrifugal action of the revolving of shaft 12 these weights move outwardly and downwardly around the point P as a center.

A freely movable sliding plunger or controlling element 18 is provided with collars 19 and 19', while the weights 15 have a contact tongue or cam 20 fitting between collars 19 and 19' and adapted to move the plunger 18 longitudinally in line with the axis of the shaft 12 as cam 20 of the weights moves upwardly and downwardly as shown. It is to be noted that the weights 15 are recessed at 21 to receive the collar 19.

Each weight 15 is connected to the control plunger 18 by a pair of springs 25, one end of each spring 25 being connected at point S to the slide or control plunger 18 and the other end connected at the point W with the weight 15, the springs being normally under tension to retain the parts in the position illustrated in Figure I when the governor is at rest with springs 25 inclined upwardly as shown in this figure. The weights 15 move outwardly around the point P as a pivot as the speed of the shaft 12 increases with the result that the cam 20 moves the collar 19 and the control plunger 18 tangentially in a vertical direction, assuming the governor to be located upright, as illustrated in Figure I. As pointed out in my copending application Serial Number 565,383, for "Governor mechanism," filed November 27, 1944, I provide a governor having a straight line curve in operation. As stated in said application, the springs 25, which have a modifying influence on the action of the weights 15 being connected at one point S to the sliding control plunger 18, assumes various positions affecting the cycle of the movement of the weights 15, and hence the anchor of the controlling spring 25 is not fixed in relation to the point W where the other end of spring 25 is connected to the weight 15. It will be noted that the point W and point S may be so chosen that the spring 25 is inclined to the horizontal when the parts are at rest as shown in Figure I in the present case. As the speed of the shaft 12 is increased the fly weights 15 move outwardly to various positions shown in Figure II and Figure III.

An important feature of the present invention is the use of the governor and combined switching means designed to open, close, or transfer circuits at definite engine speeds. In the embodiment illustrated in Figures I through IV, the governor mechanism is associated with a single switch that transfers its contact when reaching a predetermined speed and transfers back again when the speed drops approximately 25% below that point. If the governor continues to operate after the cut out, the weights 15 will fly out still further tending to greatly increase the pressure on the upwardly sliding plunger 18. A principal feature of the present invention is to provide efficient means for satisfactory operation in this type of mechanism. To this end, the plunger 18 is made in multiple parts with a loaded spring interposed therein so that until its switch operating action, the plunger parts operate in unison, but thereafter continued pressure due to increased centrifugal force of the outwardly moving weights, the loaded plunger spring is compressed and weights may come to their various natural positions up to the maximum speed to which the governor shaft may be subjected.

Referring to Figures II and III, it will be seen that the plunger 18 has a hollow open end 30 within which the compressible spring 32 is located, the spring tension of which should be sufficient for the operation of the switch before compression. This loaded spring 32 is retained within the upper end of the plunger 18 by the sliding stud shaft 34 bearing at its lower end against the spring 32, as shown, said stud shaft 34 having a shoulder 35 adapted to contact a flange 36 on the upper end of the hollow plunger 18 thus retaining the stud 34 in position.

At its upper end the stud 34 carries a thrust ball bearing 40 retained by having a press fit on the upper end of said stud 34. Surrounding the outer part of the ball bearing is the flange of the actual contact piece 42 adapted to operate the switch contact pin 43. Connected with the contact piece 42 is a spider 45 adapted to contact at its outer edges with stops 46 on the inner case of the housing 5 to prevent spinning or rotating of the upper portion of the ball bearing and contact piece 42. The member 45 or other type of suitable cage for the ball bearing is dished shaped as shown to form an oil well or reservoir 47 having an opening 48 communicating with the ball bearing 40 to lubricate the latter. Thus the contact 42 does not revolve with the governor parts.

In Figure XIV, I have illustrated partly diagrammatically a type of snap switch which I have used in my invention. The contacts 65 and 66, to be opened or closed by the mechanism, are intended to control the circuit for operating the mechanism with which the governor control is to be used such as gear shifting, clutch and valve controlling and the like. One of these switch contacts 65 is stationary and located on an insulating block 67. The movable contact 66 is mounted on a pivoted arm 68, the switch mechanism having the center switch leaf 70 to be actuated by the pin 43. A finger 71, is integral with the clamping plate and held in place by the screw 73, arranged to assert a constant pressure on the center switch leaf member 70 to open the contacts when the actuating pin 43 is released and also to return the pin 43 to its normal downwardly extending position. A snap spring connector 75 is interposed between leaf 70 and switch contact arm 68 near the contact 66 which facilitates throwing the contact 66 to either open position or to closed position depending on the position of the controlling pin 43 and is positive in its operation and action.

Of course, many other types of switches may be used with my invention.

From the foregoing it will be seen that as the speed increases, the parts move from the position shown in Figure I to that shown in Figure II to first operate the switch 44. The switch 44 may operate many types of mechanisms by electrically changing circuits to such mechanisms or to electrical or pneumatic controlling arrangements for such mechanisms. The loaded spring 32 is at this time in its extended or non-compressed position as illustrated. Thereafter upon an increase in speed, the parts assume the position illustrated in Figure III in which the contact piece 42 is still in contact with pin 43, but the spring 32 is compressed (as shown) and upon such further increases in speeds occurring after the top or contact piece 42 of the sliding multi part plunger has reached the maximum of its movement, the action of the fly weights 15 results in compressing the plunger spring, thus relieving the possibility of further or unduly increasing the pressure on the top of the plunger which would otherwise occur. The mechanism

also permits the fly weights 15 to come to their natural mechanical position under such conditions. When the speed of shaft 12 decreases the spring 32 first returns to the position illustrated in Figure II as the fly weights 15 move inwardly and upon still further decrease, the end pressure on contact 42 is removed from the pin 43 whereupon the switch mechanism 44 which is of various types, one shown in Figure XIV such as those having spring means incorporated therein to reset the switch, is returned to normal position, or in the lowered position of Figure I for the pin 43. Moreover, the pin 43 may be the operating plunger of a snap switch, this type being very sensitive and accurate in operation. By turning the knurled ring 7 clockwise the switch means hereinafter set forth will be moved farther away from the governor control element (plunger) and hence this adjustment will increase the speed at which the switches will be operated as will hereinafter appear. Turning the knurled ring 7 counterclockwise will have the opposite effect.

My invention also includes the use of a governor such as the one shown in Figures I to IV or a similar "straight line" governor such as shown in my prior application with or without using the spring loaded governor plunger in combination with an automatically resettable switch mechanism which operates to shut down the entire mechanism including the engine or the other type of mechanical means which drive the governor shaft, but which will automatically reset itself as the speed decreases ready to repeat the action upon future operations of the entire mechanism. Thus, the switch 44 actuated by pin 43 may be of an instantaneous tripping type which operates to cut off the engine at a predetermined speed and thus stop the governor shaft and which will automatically reset itself ready for the next operation. With self setting switches it may be necessary to have a self holding relay for satisfactory operation.

Under certain conditions, I may use a governor mechanism illustrated with a switch which is actuated in one direction by the pin 43 to cut off a circuit (and thus stop the engine for example) but which has to be manually reset.

In the embodiment illustrated in Figures V through IX, I have illustrated a two stage governor and switching mechanism containing two switches, each operating independently at different speeds. By means of external adjustments both the operation of the switches in relation to the engine speed and the differential between the action of the two switches may be varied. Incorporated in this embodiment is means whereby the first switch will transfer its circuit at a certain R. P. M. thereafter the second switch will be operated as the speed of the governor shaft further increases and reaches another higher predetermined speed. On reverse, as the speed is decreased the second switch will retransfer back to its initial position at a predetermined speed below its initial operation.

As one efficient mechanism embodying these features, I have illustrated in Figures V to IX the three part governor housing 5, the shaft 12, fly weights 15, and multiple part sliding plunger 18, as in the embodiment of Figures I to IV. However, in the present instance the contact 42, instead of directly operating the switch pin 43, acts upon a switch lever 50, preferably of the construction illustrated in section in Figures VI and VII. This lever 50 "floats" but is arranged to pivot first at one end and then at the other to

properly operate the two switch pins 43' and 43'' at different times. To this end, the lever 50 has on one end a depression or bearing 52 fitting on a pivot 53 as shown. The lever also has a bearing 54 for receiving the contact 42 and two bearings 55 and 56 adapted to contact the switch pins 43' and 43'' respectively. As the multiple plunger 18 moves upwardly under the influence of the fly weights 15, the lever 50 pivots at 53 so that pin 43' is first operated. The other switch pin is subsequently operated as the speed of the governor shaft increases, and to this end I have provided an adjustable loaded spring mechanism to determine when this will occur. Thus, as shown in Figure VI, the pivot 53 is supported in a housing 60 which contains a compressible spring 61, the position of the upper end of which is adjustably determined by the adjusting screw 62 threaded into the end of the housing 60. When the pressure moving the plunger 18 upwardly is sufficient to overcome the pressure of the spring 61, the pivot 53, shown at the right hand in Figure VI, gives away, whereupon the lever 50 becomes pivoted at the other side of the housing. Upon further movement, the second switch pin 43'' is operated. This action is illustrated in Figure VII where it will be seen that spring 61 has been compressed compared to the position of the parts in Figures V and VI, while the loaded plunger spring 32 remains in uncompressed position as illustrated during both switch operations in this embodiment. As the speed of the governor increases beyond the speed at which the second switch 43'' is operated, it will be seen that the plunger spring 32 will thereafter be compressed as illustrated in Figure VIII and the fly weights may come to their natural mechanical rest without imposing too great a pressure on the contact 42, floating switch lever 50, pins 43' and 43'' and all the associated parts since the loaded plunger spring 32 absorbs excess thrust.

One use of the embodiment of my governor and switch mechanism illustrated in Figures V through IX is for electrically controlling pneumatically operated gear shifting mechanisms, for example.

When at rest, the parts are as illustrated in Figure V and the switch pins 43' and 43'' are in their lowered normal position. As the speed increases, the governor weights 15 fly outwardly and the telescopic multiple part plunger 18 operates through the contact 42, the floating lever 50 which pivots around the pivot 53 during this operation. Actuation of switch 43' is arranged to electrically control shifting, for example, from low gear into second gear. Upon further increase of speed the pressure overcomes the resistance of spring 61 whereupon the floating lever 50 moves upwardly and pivots at the left hand side of the housing top to throw the switch pin 43''. This is connected electrically with a means for shifting the gears, for example, from second to high (on an automobile). By a proper adjustment of the adjusting screw 62, the differential between the action of the two switches may be varied as desired.

In connection with the operation of the two-stage circuit control mechanism illustrated in the embodiment of Figures V to IX, Figures XI, XII, and XIII represent performance curves of apparatus I have made, using various adjustments of the adjusting ring 7 and the differential screw 62. The adjustment of the screw 62 determines the spacing in speed of operation of the governor at which the second switch 43'' operates as compared with the first switch 43'. On the other

hand, the adjustment of the ring 7 determines the speeds at which the whole mechanism operates under a given adjustment of the screw 62 for various speeds of governor shaft.

The curves illustrated in Figure XI were made with the differential screw 62 adjusted to a minimum and held constant at that point. Curve A represents the speed at which the first switch 43' operates while curve B illustrates the speed at which the second switch 43'' operates. These occur in sequences upon acceleration of the governor shaft, these revolutions being illustrated in the vertical column in the left hand side of the chart while the number of turns of the adjusting ring 7 are illustrated in the horizontal line at the bottom beginning at the lower left hand corner. Upon deceleration, the curve C represents when the second switch 43'' will be disconnected and the 4th curve D represents when the first switch 43' is cut off. For example, if the adjusting ring 7, according to the curves illustrated in Figure XI, is adjusted two turns clockwise, then the first switch 43' will operate about 1300 R. P. M. of the governor shaft. The second switch 43'' will operate at about 1575 R. P. M. Upon deceleration the second switch 43'' cuts out at about 1450 R. P. M. of the governor shaft, while the first switch 43' cuts out at about 1175 R. P. M.

Referring to Figure XII, in this case the illustrations are similar to that of Figure XI, excepting that now the adjusting screw 62 for the differential action between the two switches 43' and 43'' is adjusted to its maximum position and held constant. It will now be seen that the operation of the second switch 43'' shown by curve B', Figure XII for two revolutions of the adjusting ring 7 does not operate until the governor shaft has reached nearly 2000 R. P. M. Upon deceleration, the switch 43'', cuts out at about 1800 R. P. M. as shown by the curve C' in Figure XIII. The first switch on deceleration, as shown by the line D' cuts out at about 1175 as in the other example of Figure XI, the same having cut in on acceleration as shown by curve A' at about 1300 R. P. M.

Figure XIII is limited to a consideration of the performance of the mechanism with a fixed position of the adjusting ring 7 but by various positions of the adjusting screw 62 which changes the relative R. P. M. at which the second switch operates compared with the first. Here, the curve A'' shows a fixed speed of 1000 R. P. M. at which the first switch 43' is cut in. The curve B'' shows the R. P. M. of governor shaft at which the second switch 43'' cuts in upon different turns of the screw 62 as indicated at the bottom horizontal line. For example, with five turns downwardly of the screw 62, the second switch 43'' cuts in at about 1700 R. P. M. of the governor shaft as shown by the line B''. The curve C' shows when this second switch cuts out which is at about 1575 R. P. M. for five turns of the adjusting screw under the example. The line D'' of Figure XIII shows the speed at which the first switch 43' cuts out, which in the embodiment tested was about 890 R. P. M. of the governor shaft.

A consideration of these curves illustrated in Figures XI, XII, and XIII, shows what various results may be produced if the two adjustments are made simultaneously, namely adjusting the ring 7 for a proposed range and thereafter adjusting the screw 62 for desired differential in the speed of operation between the switch 43' and switch 43''. This indicates that my invention has

a very wide range of adaptability for operating various circuits.

In Figure X I have illustrated in lieu of the ball bearing between the upper part of the telescoping plunger 18 and the contact 42, a modification which may be used with either of the embodiments of Figures I to IV or Figures V to IX. In this case, the upper contact piece 42 is of hardened metal such as carboid and is connected with the stud shaft 34 which in turn contacts with the loaded compressible spring 32 sliding within the upper open end 30 of the plunger 18 as in the other embodiments.

It is apparent that within the scope of the invention, modifications and different arrangements may be made other than is herein disclosed, and the present disclosure is illustrative merely, the invention comprehending all variations thereof.

20 What I claim is:

1. The combination of a governor housing; a driving shaft carried by said housing; centrifugally operated fly weights surrounding said shaft and rotated thereby; a sliding plunger operated by said weights; a switch operating lever; a plurality of switch actuating elements; means to move said switch lever from said plunger; arranged whereby said lever is first moved to operate one of said switch elements and upon continued pressure of said sliding plunger subsequently operates the other of said switch elements when the speed of the governor shaft increases.

2. The combination of a governor housing; a driving shaft carried by said housing; centrifugally operated fly weights surrounding said shaft and rotated thereby; an articulated spring loaded sliding plunger operated by said weights; a plurality of switch operating elements; a switch lever; means to move said lever from said plunger; the mechanism arranged whereby said lever is first moved to operate one of said switch elements and upon increased speed and continued pressure of said plunger to subsequently operate the other of said switch elements, the spring of said governor plunger adapted to yield upon still further increase in speed of said driving shaft.

3. The combination of a governor housing; a driving shaft carried by said housing; centrifugally operated fly weights surrounding said shaft and rotated thereby; a sliding plunger operated by said weights; a floating transverse switch operating lever; means to move said lever from said plunger; spaced movable switch pins carried by said governor housing; and means forming a plurality of pivots for said switch lever including a spring loaded movable pivot, said pivoting means carried by said governor housing and arranged whereby said lever is first pivoted from said movable pivot to operate one of said switch elements and upon continued pressure of said sliding plunger subsequently operates to actuate the other of said switch pins.

4. The combination of a governor housing; a driving shaft carried by said housing; centrifugally operated fly weights surrounding said shaft and rotated thereby; an articulated spring loaded sliding plunger operated by said weights; a floating transverse switch lever; means to move said lever from said plunger; spaced movable switch pins carried by said governor housing; and means forming a plurality of pivots for said switch lever including a spring loaded movable pivot, said pivoting means carried by said governor housing, the mechanism arranged whereby

said lever is first pivoted to operate one of said switch pins and upon increased speed and continued pressure of said plunger subsequently operates to actuate the other of said switch elements, the spring of said governor plunger adapted to yield upon still further increase in speed of said driving shaft.

5. The combination of a governor housing; a driving shaft carried by said housing; centrifugally operated fly weights surrounding said shaft and rotated thereby; an articulate spring loaded sliding plunger operated by said weights; a floating transverse switch lever; means to move said lever from said plunger; spaced movable switch pins carried by said governor housing; and means forming a plurality of pivots for said switch lever including a spring loaded movable pivot, said pivoting means carried by said governor housing, the mechanism arranged whereby said lever is first pivoted to operate one of said switch pins and upon increased speed and continued pressure of said plunger subsequently operates to actuate the other of said switch elements, the spring of said governor plunger adapted to yield upon still further increase in speed of said driving shaft.

6. The combination of a governor housing; a driving shaft carried by said housing; centrifugally operated fly weights surrounding said shaft and rotated thereby; an articulated spring loaded sliding plunger operated by said weights; a floating transverse switch lever; means to move said lever from said plunger; a ball thrust bearing between said plunger and said lever; spaced movable switch pins carried by said governor housing; and means forming a plurality of pivots for said switch lever including a spring loaded movable pivot, said pivoting means carried by said governor housing, the mechanism arranged whereby said lever is first pivoted to operate one of said switch pins and upon increased speed and continued pressure of said plunger subsequently operates to actuate the other of said switch elements, the spring of said governor plunger adapted to yield upon still further increase in speed of said driving shaft and means to prevent rotation of said lever moving means.

7. In combination, a governor housing; a driving shaft mounted therein, fly weights surrounding said shaft and driven thereby; a sliding plunger operated by said fly weights, said plunger having a cylindrical open bore in its outer end; a loaded spring in said bore; a movable member

5 in said bore above said spring; a contact operating element; a thrust ball bearing interposed between said member and said contact to take the thrust when the pressure of the plunger is sufficient to overcome the resistance of said loaded spring; and means to prevent the outer cage of said ball bearing and said contact element from rotating, said means including a spider contacting the governor housing said spider having a dished shaped center forming an oil well for receiving lubricating oil and an opening therefor into the ball bearing.

10 8. In combination of a governor having a driving shaft; centrifugally operated fly weights surrounding said shaft and rotated thereby; a movable controlling member operated by said weights; a plurality of switch actuating elements; a switch operating lever; means to move said switch lever from said controlling member whereby said lever is first moved to operate one of said switch actuating elements at one speed and when the speed of the governor shaft further increases to subsequently operate the other of said switch actuating elements; and means to vary the differential in the speeds at which said switch actuating elements are operated.

15 9. In combination, a governor housing; a driving shaft mounted therein, fly weights surrounding said shaft and driven thereby; a sliding plunger operated by said fly weights, said plunger having a cylindrical open bore in its outer end; a loaded spring in said bore; a movable member in said bore above said spring; a contact operating element; a thrust ball bearing interposed between said member and said contact to take the thrust when the pressure of the plunger is sufficient to overcome the resistance of said loaded spring; and means to prevent the outer cage of said ball bearing and said contact element from rotating, said means including a member interposed between said outer cage of said ball bearing and the governor housing.
